UNITED STATES PATENT OFFICE.

NOAH S. HARTER, OF WAUKEGAN, ILLINOIS, ASSIGNOR TO THE AMERICAN STEEL & WIRE COMPANY OF NEW JERSEY, OF HOBOKEN, NEW JERSEY, A CORPORATION OF NEW JERSEY.

APPARATUS FOR COILING AND BENDING HELICAL SPRINGS.

1,050,363.

Specification of Letters Patent. Patented Jan. 14, 1913.

Application filed January 30, 1911. Serial No. 505,578.

To all whom it may concern:

Be it known that I, NOAH S. HARTER, of Waukegan, in the county of Lake and State of Illinois, have invented a new and useful 5 Apparatus for Coiling and Bending Helical Springs, of which the following is a full, clear, and exact description, reference being had to the accompanying drawings, forming part of this specification.

10 My invention relates to apparatus used for making or forming helical springs from a bundle or coil of wire and the invention more particularly relates to apparatus for forming springs having a bend on one end 15 or on the opposite ends of the completed springs.

One object of my invention is to provide 20 spring forming mechanism having improved means for winding springs from a coil or bundle of wire, means for varying the lengths of the springs, and having improved means for forming a bend on the forward end of the springs.

Another object of this invention is to provide 25 a spring coiling mechanism having means for severing the coiled springs from the bundle or coil of wire, and having means for forming a second bend on the severed or last formed end of the wound spring.

30 A further object of the invention is to provide spring forming apparatus having novel means for actuating the cutting and bending mechanisms.

In the accompanying drawings, Figure 1 35 is a plan showing spring making apparatus constructed and arranged in accordance with my invention. Fig. 2 is a longitudinal side elevation of the same. Fig. 3 is a perspective view looking from the rear end 40 of the apparatus. Fig. 4 is a front end elevation of the apparatus illustrated in Figs. 1, 2 and 3. Fig. 5 is a detail sectional plan, on a larger scale, showing the winding and bending mechanisms forming part of this 45 invention. Fig. 6 is a detail end elevation of the shearing and coiling mechanisms shown in Fig. 5. Fig. 7 is an enlarged detail side elevation showing the mechanism for operating the bending tool in forming 50 the bend upon the forward or first coiled end of the spring. Fig. 8 is a detail sectional plan and Fig. 9 is an end elevation showing a modified form of the mechanism for operating the bending tool, this figure

showing the end of the coil of wire from 55 which the springs are made having a bend as formed thereon with my improved apparatus at the beginning of the spring forming operations. Fig. 10 is a sectional plan and Fig. 11 is an end elevation showing the 60 means employed in forming a bend on the opposite or rear end of the springs after severing the coiled or wound springs from the coil or bundle of wire forming the stock 65 from which the springs are made.

Referring to the drawings, 2 designates 70 the base or main frame of the apparatus supported upon legs or standards 3, 3, 4, 4, upon which the coiling, shearing and bending mechanisms are mounted. Secured in 75 bearings 5 on the frame 2 is a horizontally extending main shaft 6 having on one end a spur gear 7 by which it is driven through the spur pinion 8 on the horizontal pulley shaft 9 which as shown is mounted in bearings 10 upon the brackets or steps 11 on the rear standards 4, 4. The shaft 9 is provided on one end with a pulley 12 through which the apparatus is connected by a belt with a similar pulley on a driving shaft or 80 other prime mover (not shown). The opposite end of the shaft 9 is provided with a hand wheel 13 which is used in adjusting the parts when operating the machine.

The spur gear 7 is provided on one side 85 with a radially extending T-slot in which the T-head of an adjustable crank pin 14 is adjustably secured so as to be movable toward and away from the axial center of the wheel 7 to vary the throw of the connecting 90 rod 15, one end of which is secured on the crank pin 14. The connecting rod 15 is attached by its other end to the crank pin 16 on the segmental gear 17 which is pivoted to the pin 18 on the lower end of the downwardly extending bracket 19 secured in place on the under side of the supporting frame 2, and which is arranged to be rocked forwardly and backwardly by the connecting rod 15 when the gear wheel 7 is rotated. 95 The segmental gear 17 meshes with the spur pinion 20 on the shaft 21 mounted in the bearings 22. This shaft in turn, through the spur gears 23, 24, 25, 26, and the gears 27 and 28, operates the hollow shaft 29 100 which is mounted in bearings 30 on the base or frame 2 of the apparatus. The shaft 31 upon which the gear 27 is mounted, is also

provided with a gear 32 which, through the gears 33, 34, is arranged to rotate the gear 35. This gear 35 is keyed or otherwise secured on the sleeve 36 which is rotatably mounted on the hollow shaft 29 for a purpose described later. The gears 33 and 34 are rotatably mounted upon supporting links 37, 38 and 39, and one of the ends of the links 37, 38, is connected by a clevis 40 to the connecting rod 41 which is arranged to hold the gears 33 and 34 in position and to rock or operate them at the desired time.

Mounted in the opening in the hollow shaft 29 is an arbor or spindle 42 around one end of which the springs are wound or coiled. The hollow shaft 29 is provided on one end with an enlarged flange portion or winding head 43 and on this head a stud or pin 44 is mounted in such manner as will catch the wire and cause it to wind around the arbor as the hollow shaft 29 and arbor 42 are rotated.

The annular sleeve 36 on the hollow shaft 29 is provided with a flange portion forming a bending head 45, and on this head is a pin or stud 46 which is arranged to catch the end of the wire at the desired time in the operation of forming the springs and form a bend thereon by bending the wire around the stud 44 on the head 43, this being clearly illustrated in Figs. 6 and 9. The head 45 is provided with a recess into which the flange or winding head 43 extends when assembled in operative position. A disk 47' having a cam groove 47 is mounted on the driving shaft 6 so as to turn with it, and a rocker arm 48 is pivoted on the pin 49 which is secured to the standard or bearing 50 on the frame 2 of the machine. The rocker arm 48 is provided with a pin 51 which is adjustable in the slot 48' on the arm, this pin being connected to one end of and operating the connecting rod 41. Adjustment in the length of the connecting rod 41 is obtained by means of the sleeve nut 41'. On the lower end of the rocker arm 48 is an anti-friction roller which operates in the cam groove 47 on the disk 47' so as to cause a rocking movement of the arm 48 when the disk 47' is rotated and through the arm 41 to reciprocate the links 37 and the gears 33 and 34 and oscillate the links 38, 39, pivoted to the shaft 31 and sleeve 36.

By referring to Figs. 2 and 7 it will be noted that a forward movement of the connecting rod 41 and the gears 33 and 34 will cause the gear wheel 35 and the sleeve 36 to rotate relative to the hollow shaft 29. The gear 35 is held in position by the gear 34, whether running or not, and should the gears 33 and 34 be held in a definite position, the relative angular movement of the hollow shaft 29 and the sleeve 36 will be the same, but should the gears 33 and 34 be reciprocated from the position shown in Fig.

7, the sleeve 36 will be rotated upon the hollow shaft 29, whether the shaft 29 is turning or not. When the sleeve 36 is rotated on the shaft 29 the stud 46 on the head 45 of the sleeve 36 will be moved relatively to the stud 44 on the head 45 of the hollow shaft 29 so as to bend the end of the wire from the straight position shown in full lines into that shown by dotted lines in Fig. 6 and by full lines in Fig. 9. This relative movement of the sleeve 36 on the shaft 29 may take place either before or during the operation of coiling or winding of the spring.

A horizontal shaft 54 is mounted in bearings on the frame 2 so as to extend at right angles to the horizontal driving shaft 6, the shaft 54 having a spur gear 55 on one end in mesh with the spur gear 56 on the end of the short horizontal shaft 56' mounted in the bearing 57 on the rear end of the frame 2. A bevel gear 58 is provided on the other end of the shaft 56' which meshes with a similar gear 59 mounted on and rotated by the shaft 6, through which the shaft 54 is driven.

On one end of the shaft 54 is a cam disk 60 having a cam recess 61 in which extends the anti-friction roller 62 which is on the end of one arm of the bell crank 63, the bell crank being pivoted by the pin 64 to the base or frame 2 of the spring forming apparatus. The other arm of the bell crank 63 is provided with a slot 63' in which a pin 65 is adjustably secured. On the end of the pin 65 is one end of the connecting arm or rod 66, the opposite end of the connecting rod 66 being secured to and operating the lever 67 which is secured to the pivot shaft 68 mounted in the bearing 69 on the frame 2 of the machine. The opposite end of the shaft 68 is provided with a lever or arm 70 having a forked upper end and secured in the forked upper end of this lever is a sleeve 71 which is mounted so as to permit the arbor 42 to freely rotate therein. Secured to the arbor 42 on the opposite sides of the fork 71, are collars 72 which are rigidly mounted on and are arranged to rotate with the arbor 42, the forked arm 70 through the sleeve 71 and collars 72 reciprocating this arbor in the hollow shaft 29 when the cam 60 is rotated, so as to rock the bell crank 63. The distance the arbor 42 is reciprocated in the hollow shaft 29 is regulated by adjustment of the pin 65 in the slot 63' in one arm of the bell crank 63 and the arbor 42 is adapted to be retracted so that its forward end is entirely within the hollow shaft 29 at intervals in the operation of the mechanism.

Mounted in a support 73 are cutters 74 and 75 in which, as shown, the top cutter 75 is reciprocated vertically so that its forward end, by co-operation with the bottom cutter 74 will sever the last formed end of the coiled spring from the forward end A of the bundle of wire from which the springs are

130

being formed. A lever or arm 76 is secured by one end on the pin or shaft 77 which is pivotally secured to the support 73 on the main frame 2, and on the other end of the pin 77 is an arm 78 having one end operatively connected with the reciprocating shear knife 75 as is best shown in Figs. 1, 2 and 4. The opposite end of the arm or lever 76 is connected at its lower end by the connecting rod 79 to the rocker arm 80 which is secured by the pin 81 to the standard or support 82 on the frame 2. The lower end of the arm 80 is provided with an anti-friction roller which extends into and engages with the sides of the cam groove 84, this groove being arranged, when the cam 84 is rotated, to cause the arm 80 to rock, and, through the connecting rod 79 and lever arms 76 and 78, to reciprocate the vertically movable shear knife 75. A sleeve nut 79' is employed on the connecting rod 79 to adjust the length of the connecting rod.

Movably mounted on the base or main frame 2 is a horizontally reciprocating slide 85 which forms the feeding mechanism by which the wire is fed forwardly in making the springs. A longitudinal slot in the slide 85 is provided with inclined side surfaces 86 on one side thereof and mounted in these slots are small rollers 87 which are arranged to roll on the inclined surfaces 86, the diametrically opposite surfaces of these rollers contacting with the wire A. Secured to the rotatable disk 88 on the shaft 6 by the pin or bolt 89' is one end of a connecting rod 89 which is also connected to the upper end of the vertically extending lever 90 which is pivotally secured by the shaft 91 to the downwardly extending arm support 92 that is rigidly secured to the frame 2 as is best shown in Fig. 2. The pin or bolt 89' is adjusted in the slot 88' in the face of the disk 88 to vary the throw of the arm 90. On the opposite end of the shaft 91 is a second lever 45 85', the upper end of which is connected to the reciprocating slide 85. It will be seen by reference to Figs. 1 and 2 that when the disk 88 is rotated the arm 90 will be rocked and the slide 85 will be reciprocated, and, on the forward movement of the slide 85, the rollers 87 will be moved by the inclined sides 86 of the slot in the slide 85 so as to tightly grip and feed forwardly the wire A, and that when the slide 85 is retracted the rollers 87 by moving in the opposite direction, will become disengaged from and release the wire A so as to not cause backward movement of the wire.

Mounted in a suitable slot in the side of the frame 2 is a slide bar 93 having on one end an anti-friction roller 94 which projects into and engages with the cam slot 95 in one face of the disk 88, the slot and anti-friction roller being shown by dotted lines in Fig. 2. 65 On the opposite end of the slide bar 93 is a

rack 96, the teeth of which mesh with the spur gear 97 on one end of the vertical shaft 98 in the bearing 99 which is secured to one side of the frame 2. On the opposite end of the shaft 98 is a second gear 100 which in turn meshes with the teeth of the rack 101 which is mounted in the horizontally extending rack support 102 and is arranged to be reciprocated by the gear 100. A pusher 103 is secured to the end of the rack 101 and is arranged to engage with and push the forward end of the wire A transversely into position relative to the arbor 42 and studs 44 and 46, to permit of the bend being formed in the end of the wire when the studs 44 and 46 are rotated with respect to each other, at the beginning of the spring forming operation, preferably.

After a spring has been formed by winding the end A of a coil or bundle of stock wire around the arbor 42, the shear knife 75 will be caused to approach the shear knife 74 so as to sever the coiled spring from the wire A. With the apparatus shown in Figs. 10 and 11, by continuing the forward movement of the knife 75, the bending portion 104 of the knife 75 will engage with the last cut or rear end of the formed spring then on the arbor 42 and bend it over the end of the support 105, as is shown in Fig. 11. The spring, 95 which by this action of the bending portion 104 of the knife is completed, is then in readiness to be removed from the arbor 42.

In the modified form of mechanism shown in Figs. 8 and 9 for actuating the bending tool or head, the connecting rod 41 is secured to one arm 111^b of the bell crank 111 which is pivoted on the pin 112 to the frame 2 of the machine. The other arm 111^a of the bell-crank 111 is forked and is operatively secured to the sleeve 108 so as to reciprocate this sleeve. The sleeve 108 is connected by a spline or feather key with the sleeve 110, so as to rotate the sleeve 110 and its pin 46 angularly, with relation to the winding head 43 and the pin 44 thereon which, in this construction, forms part of the hollow shaft 106.

In the operation of my improved apparatus, each complete revolution of the driving shaft 6 makes a complete cycle of movements of the working parts. After the end of the wire A has been put in position in the reciprocating slide 85 so as to project beyond the cutters 74 and 75, the wire A is caused to move forwardly by the reciprocating slide 85 during the time the shaft 6 is being turned through a half revolution. The length of wire fed forwardly beyond the ends of the cutters is variable and depends upon the adjustment of the pin 89' in the disk 88. The greater the distance this pin is placed from the axis of the shaft 6 on which the disk is mounted, the greater the amount of wire fed forwardly. As soon as the wire is advanced to the proper position, the cam

70
75

110

115

120

125

130

will operate the pusher 103 to move the wire transversely into position in under the stud 44, as is shown by Fig. 6. The wire A being fed forwardly in a plane outside of the end of the studs 44 and 46 by the slide 85 will 5 clear and not become fouled by these studs during backward movement of the head 43. The connecting rod 15, when it crosses the vertical center of the shaft 6, starts the rotating movement of the hollow shaft 29 and 10 the stud 44 which movement will cause the wire to wind around the arbor 42. The number of turns wound on the arbor 42 is varied by adjusting the crank pin 14 on the spur gear 7 so as to increase or decrease the 15 length of stroke or angle of rotation of the segmental gear 17. As soon as the winding operation is started, the pusher will be retracted so as to give clearance for the rotating end of the wire A. The winding operation 20 is then continued until the shaft 6 has been rotated through a half revolution and, either during the winding of the wire to form the spring or just prior to the time the 25 winding operation is started, the cam 47 will actuate the connecting rod 41 and rock the arm 38. When the arm 38 is rocked by the rod 41 the gear 33 will rotate the gears 34, 35, and by the rotation of the gear 35 30 will change the relative angular position of the hollow shaft 29 with respect to the sleeve 36 so as to cause the stud 46 to catch the end of the wire and produce a bend in the end of the wire around the stud 44, as is 35 illustrated in Fig. 6. Each wrap or coil of the wire on the mandrel forms a guide for the next formed coil or wrap during the wire coiling or winding operations. Should the coiling mechanism shown in Figs. 8 40 and 9 be employed instead of that shown in Figs. 10 and 11, the operation as above described will be the same, in this case the helically threaded portion 109 of the shaft 107 and the internally threaded 45 sleeve 108, which is splined by the feathers 109 to the sleeve 110, taking the place of the spur gears 35, 34, 32, 33, shown in Figs. 1 to 3. As shown in Figs. 8 and 9, the sleeve 108 is connected to the forked arm 111^a of 50 the bell crank 111 which is pivoted at 112, on the frame 2 of the machine, the opposite arm 111^b being operatively connected to the end of the rod 41 through which the coiling mechanisms of both constructions are actuated. The amount of bend produced on this 55 forward end of the springs may be varied by adjusting the pivot pin 51 in the slot 48' in the arm 48. After the winding operation has continued during the time the shaft 6 is 60 rotating a half revolution, the rotative movement of the hollow shaft 29 will stop, preparatory to beginning the backward or reverse movement of the shaft 29, and during this time the cutter 75 will be reciprocated 65 so as to sever the wire forming the wound

spring from the coil or bundle, and, when the bending member 104 is employed, produce a second bend on the other end of the spring, as is shown in Fig. 10. The amount of bend and the position of the bend on the rear end of the formed springs may be varied according to the shape and position of the tools employed. The movements above described completing the winding, cutting and bending operation, the shaft 29 commences to rotate in the opposite direction, and at the instant the segmental gear 17 begins its backward movement. When the backward movement begins, the cam 69 will operate through the connecting mechanism 70 to reciprocate the arbor 42 within the hollow shaft 29 and withdraw the forward end of this arbor within the hollow shaft, in this way stripping the arbor from the spring just formed, so as to permit of the spring 75 falling through the opening provided in the base 2 for that purpose. The arbor will then be moved back so as to again project through the end of the hollow shaft, in position for the next winding operation, and while the hollow shaft 29 is being rotated in the reverse direction to that used for winding. At the same time the rod 41 will move 80 backwardly so as to rock the gears 33 and 34 and move the gear 35 so as to cause the pin 85 or stud 46 to again assume its position relative to the pin 44 and mandrel 42 shown in Fig. 6. The wire A will then be again moved forwardly into position by the slide 85, as has been before described and the 90 above described operations will then again be repeated in forming another spring. 95

The advantages of my invention will be apparent to those skilled in the art. The apparatus is simple and is easily kept in repair. By its use a bundle or coil of wire is mechanically formed into a plurality of separate springs. The formed springs are successively cut from the end of the bundle of wire and the opposite ends of each spring 100 are provided with a bend of the desired shape and in the required relative angular position. 105

Modifications in the construction and arrangement of the parts may be made without departing from my invention as described in the specification and defined in 110 the appended claims. 115

I claim:-

1. In apparatus for coiling and bending 120 springs, a hollow coiling head having an outwardly projecting pin in one face thereof, a hollow bending head on the periphery of said coiling head having an outwardly projecting pin on one face thereof, means for rotating said heads in unison, and mechanism for relatively moving said heads. 125

2. In apparatus for coiling and bending wire spring, a mandrel, a hollow spindle having a winding head in which the mandrel 130

is mounted to move longitudinally, means on the head for engaging with the wire stock, a hollow shaft in which the spindle is movably mounted having a bending head 5 thereon; means on said bending head engaging with the wire stock, means for severing the formed spring from the wire stock, and mechanism constructed and arranged to operate the heads consecutively to 10 bend the end of the wire, wind the wire around the mandrel to form a spring and sever the coiled spring from the wire stock.

3. In apparatus for coiling and bending wire springs, a mandrel, a hollow spindle 15 having a winding head in which the mandrel is mounted to move longitudinally, means on the head for engaging with the wire stock, a hollow shaft in which the spindle is movably mounted having a bending 20 head thereon, means on said bending head engaging with the spring wire, means for severing the formed springs from the wire stock and forming a bend on the severed end of the spring, and mechanism constructed 25 and arranged to operate the heads consecutively to bend the end of the wire, wind the wire around the mandrel to form a spring, sever the coiled spring from the wire stock and form a bend on the other end 30 of the wire forming the spring.

4. In apparatus for forming wire springs, the combination of means for forming a bend on the end of the wire stock, adjustable means for coiling the end of the wire stock 35 into a spring, means for severing the coiled spring from the wire stock, mechanism for actuating said several means consecutively in the order named, and means for varying the rotative movement of the coiling means.

40 5. In apparatus for forming wire springs, the combination of mechanism for forming a bend on the end of the wire stock, means for feeding forwardly the wire stock into position for forming said bend, mechanism 45 for coiling the end of the wire stock into a spring, means for severing the coiled spring from the wire stock, means for forming a bend on the severed end of the spring, mechanism for actuating said several means

and mechanisms consecutively, and means 50 for adjusting the length of movement of said feeding means to vary the length of the bend formed on the end of said springs.

6. Apparatus for forming wire into 55 springs, having a mandrel, a rotatable coiling head arranged to bend the wire around said mandrel, a rotatable bending head, and means for actuating said heads in unison, means arranged to cause a relative movement of the bending and coiling heads to form a 60 bend on the end of the wire, and means for varying the rotative movement of the coiling head, to change the length of the springs.

7. Apparatus for forming wire into 65 springs, having a mandrel, a hollow rotatable coiling head, a rotatable bending head mounted in said coiling head, means for actuating said heads, said means being constructed and arranged to cause a relative movement of the bending and coiling heads 70 to form a bend on the end of the wire, and means for severing the coiled springs from the wire stock.

8. Apparatus for forming wire into 75 springs having a reciprocating mandrel, a rotatable coiling head, a rotatable bending head, means for actuating said heads, and means for moving the reciprocating mandrel to strip the completed springs therefrom.

9. Apparatus for forming wire into 80 springs having a reciprocating mandrel, a rotatable hollow coiling head in which said mandrel is mounted, a rotatable bending head, means for actuating said heads, said means being constructed and arranged to 85 cause a relative movement of the bending and coiling heads to form a bend on the end of the wire, means for severing the coiled springs from the wire stock, and means for moving the reciprocating mandrel to strip 90 the formed springs therefrom.

In testimony whereof, I have hereunto set my hand.

NOAH S. HARTER.
